UNITED STATES PATENT OFFICE.

CHARLES F. HOLYBEE, OF HOTCHKISS, COLORADO.

PLATE-HOLDER.

1,159,673.

Specification of Letters Patent.

Patented Nov. 9, 1915.

Application filed August 12, 1914. Serial No. 856,450.

To all whom it may concern:

Be it known that I, CHARLES F. HOLYBEE, a citizen of the United States, residing at Hotchkiss, in the county of Delta and State 5 of Colorado, have invented certain new and useful Improvements in Plate-Holders, of which the following is a specification, reference being had to the accompanying drawings.

10 This invention relates to certain new and useful improvements in devices of that character designed for the purpose of holding plates on tables or other supports and has for its primary object to produce a very simple and effective device of this character for securely holding a child's plate upon a table whereby all liability of the same being accidentally knocked off and broken is obviated.

20 In its more specific aspect, the invention has for a further object to provide a device of the above character constructed from a single length of resilient steel wire provided with a central elongated loop adapted for 25 engagement against the under side of the table and a pair of arms having outwardly bowed portions for clamping engagement against opposite sides of the plate rim, said arms being formed with inwardly extended 30 hooks to engage over the edge of said rim.

The invention has for a further general object to provide a plate holder which is extremely simple in its construction and may therefore be produced at a small cost, and 35 one which will also occupy but little room upon the table, is strong and durable in construction and neat in appearance.

With the above and other objects in view, the invention consists in novel features of 40 construction, combination and arrangement of parts as will be hereinafter referred to and more particularly pointed out in the specification and claim.

For a full understanding of the invention, 45 reference is to be had to the following description and accompanying drawing, in which—

Figure 1 is a perspective view illustrating the manner of application of my device; 50 Fig. 2 is a side elevation thereof, the normal condition of the holder being illustrated in dotted lines; and Fig. 3 is a top plan view.

As above stated, my improved plate holder is devised primarily to prevent children 55 from pushing or accidentally knocking the plate from the table, though it will be un-

derstood that the device may also be advantageously used upon shipboard or other places where the employment of clamping devices of this character is a recognized necessity. To this end, I form the plate holder from a single length of resilient steel wire of proper gage, the same being provided with an elongated central loop 5, the opposite sides of which extend in divergent 60 relation from its intermediate or bight portion. From the ends of this wire loop the wire is extended laterally and curved in substantially semi-circular form, as indicated at 6, for engagement with the edge of the table, as will be noted from reference to the drawings. The resilient wire is then extended from the curved portion 6 toward the central portion of the loop 5 and outwardly with respect to the opposite side portions of 65 said loop, as indicated at 7. These portions of the wire are bent upon themselves and inwardly curved to produce the hooks 8. From said hooks, the end portions of the wire which extend beyond the central part 70 of the loop 5 are outwardly bowed, as at 9, and terminate in the inwardly projecting hooks 10.

The manner of using or applying my improved plate holder will be clearly understood from reference to Figs. 1 and 2 of the drawings. Normally, the central loop 5 of the wire holder converges toward the end portions of the wire in which the bowed arms 9 are formed, and in order to apply 80 the device to the edge of the table, it will be understood that this loop must be sprung away from said arms. The edge of the table is received between the loop 5 and the portions 7 and 9 of the wire which extend over 85 the upper surface of the table. The plate indicated at P in the drawings having been arranged between the arms 9 and the hooks 8 and 10 engaged over the edge of the plate rim, it will be manifest that the spring tension of the wire portion 7 and of the loop 5 will effectually prevent a shifting movement of the holder upon the table. The base 90 of the plate is thus at all times held in close contact with the table surface. By the provision of the bowed portions 9 of the holder which are also longitudinally curved to bear upon the surface of the table, it will be manifest that a pressure upon the edge of the plate rim, which may tend to tilt the 95 same, operates to cause a further bowing of these portions of the wires to thereby in-

- crease their clamping pressure upon the table surface and thus effectively preclude the upsetting or overturning of the plate or its disengagement from the retaining hooks 8 and 10. In this manner, it will be appreciated that the plate is securely held in position, and cannot be knocked from the table and broken, even though it may be struck a hard blow, either accidentally or otherwise.
- 10 If desired, the wire of which the device is formed may be covered with cloth or other material in order that the polished surface of the table will not be marred by the clamping action of the device thereon.
- 15 From the foregoing description, it will be seen that I have produced a simple and inexpensive plate holder or clamp which is very efficient and reliable for the purpose in view. The holder may be very easily applied to the 20 table and the plate, or removed therefrom. The device may of course be manufactured in various sizes, and is also susceptible of various minor changes in the form and proportions of the several structural features 25 thereof, I therefore reserve the privilege of

resorting to all such legitimate modifications which may fairly fall within the spirit and scope of the invention as claimed.

I claim:

A plate holder formed from a single 30 length of resilient wire bent to provide a central elongated loop, said wire being bent upon itself from the ends of the side portions of the loop, said loop and the returned portions of the wire being adapted for 35 clamping engagement upon the upper and lower surfaces, respectively, of a table, the end portions of the wire extending beyond the central bend thereof and being outwardly bowed and longitudinally curved for 40 bearing engagement upon the upper surface of the table, said wire end portions each having a plurality of hooks formed therein for engagement with the rim of said plate.

In testimony whereof I hereunto affix my 45 signature in the presence of two witnesses.

CHARLES F. HOLYBEE.
